(57) **CLAIM**

The ornamental design for fishing rod line guide as shown and described.

DESCRIPTION

FIG. 1 is a perspective view of a spinning model fishing rod line guide;

FIG. 2 is a side view of the spinning model fishing rod line guide;

FIG. 3 is a front view of the spinning model fishing rod line guide;

FIG. 4 is a side view of a second embodiment of a spinning model fishing rod line guide;

FIG. 5 is a front view of the second embodiment of the spinning model fishing rod line guide;

FIG. 6 is a side view of a third embodiment of a spinning model fishing rod line guide;

FIG. 7 is a front view of the third embodiment of the spinning model fishing rod line guide;

FIG. 8 is a perspective view of a casting model fishing rod line guide;

FIG. 9 is a front view of the cast model fishing rod line guide;

FIG. 10 is a side view of the casting model fishing rod line guide;

FIG. 11 is a front view of a second embodiment of a casting model fishing rod line guide;

FIG. 12 is a side view of the second embodiment of the casting model fishing rod line guide;

FIG. 13 is a front view of a third embodiment of a casting model fishing rod line guide;

FIG. 14 is a side view of the third embodiment of the casting model fishing rod line guide;

FIG. 15 is a front view of a fourth embodiment of a casting model fishing rod line guide;

FIG. 16 is a side view of the fourth embodiment of the casting model fishing rod line guide; and,

FIG. 17 is a perspective view of a running line guide.
